UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP CAR.

Application filed May 15, 1925. Serial No. 30,416.

My invention relates to improvements in dump cars.

It is an object of my invention to improve the dumping doors of cars; also the means associated therewith for supporting the doors in closed position and for releasing the same.

It is also an object of my invention to provide supporting means for dump car doors which will release in unison, and to provide means whereby the locking of one element in a plurality of associated locking elements will also lock other elements in the series.

Other and further objects of the invention will more fully and clearly appear from the description and claims hereinafter following.

In the drawings Figure 1 is a side elevational view of a part of a car showing my improved construction incorporated therein. Figure 2 is a vertical sectional view taken through the car and showing slightly more than one half thereof, said section being taken on a line corresponding substantially to the line 2-2 of Figure 1. Figure 3 is a view of the door locking mechanism shown in Figure 1, on an enlarged scale. Figure 4 is a vertical sectional view through the outer end of the door, and is taken on a line corresponding to the line 4-4 of Figure 3.

In said drawings A denotes the side of the car; B the center sill construction; C cross-beams extending outwardly from the sills to the side of the car; C' bolsters also extending across the car; D a dumping door hinged to the center sill, having projecting floor beams E-E extending beyond the free edge thereof; F and G designate the door supporting means adapted to respectively engage the respective floor beams E-E of the door to maintain the door in locked position; H a connection between the respective means F and G to cause the locking elements to function in unison; and J designates the door supporting member adapted to arrest the downward movement of the door.

The side A of the car is shown as composed of planks carried by a frame which preferably includes a lower chord member 10, having a horizontally disposed flange 11, and a vertically extending flange 12, the flange 11 resting upon the ends of the cross-beams and bolsters. Side stakes 13 rise vertically from the ends of the crossbeams or

bolsters, each being secured to its respective cross member and to the flange 12. The diagonal members of the side wall are indicated at 14, and a gusset 15 is shown as connecting one of the diagonal members with the vertical stake 13. The center sill B preferably includes two channels 16-16 having a cover plate 17 connecting the same. Each crossbeam C consists of a shallow diaphragm 18, with a surmounting cover plate 19, extending from side to side of the car. The bolster diaphragms 118 are formed of a somewhat deeper section than those of the crossbeams and are connected across the plane of the center sill by a bottom plate 218.

The dumping door D is preferably formed of metal as shown, having a series of rigidifying embossments 20 in the form of corrugations preferably pressed above the plane of the door plate and extending from the hinged end of the door towards the free edge thereof. The margins of the door are flanged at the side edges as at 21, and at the front and rear edges as indicated at 22 and 23, respectively. Each door is pivotally mounted at its rear on three hinge butts 24, secured to the center sill, there being a corresponding number of hinge straps 25 on the door, which extend through the rear flange 23 thereof, each strap 25 being formed with a hinge eye 26 through which the pivot pin 27 extends to connect the same with its corresponding hinge butt 24. The hinge straps 25 adjacent the side edges of the door are united to the door with longitudinally extending reinforcing angle shaped members 126 which extend towards the free end of the door and connect with the flange of a bar 127, which extends from side edge to side edge of the door.

The outer or swinging edge of the door is supported from the car through the medium of the door supporting means F and G, engaging the outer ends of the door beams E-E.

The door supporting means F and G, respectively, include shouldered latch elements 44 and 45, pivotally mounted in brackets respectively indicated at 46 and 47. The bracket 46, preferably a casting, is provided with angularly related walls including a main back wall 48, and a horizontally extending wall 49, said walls when the bracket is in position, being adapted to bear against

the respective flanges 12 and 11 of the lower chord of the side, and being securely riveted thereto. To provide a housing, and also provide against outward bending or movement of the latch, the bracket 46 is formed with an outer wall or web 148 united to the main back wall 48 by a wall 50 of irregular contour which provides front and rear limiting stops as indicated at 51 and 52 respectively for the latch member 44, which is pivotally mounted at 53 and adapted to have swinging movement between said walls 48 and 148. The latch member 44 is formed with a shank 53 having the upper portion thereof sloping downwardly from its pivotal support and away from the corresponding floor beam E. At the bottom of the shank is provided a shoulder or curved bearing face 55 which is formed to correspond substantially to the curve of the ledge 42 on the beam E, said latch member below said shoulder 55 being formed with a depending handle 56, and intermediate the handle 56 and the shoulder 55, the latch is formed with a tapered face 57 adapted to be engaged by the related door beam E to displace the latch out of the path of said beam, as the door moves towards closed position, it being understood that the respective latches 44 and 45 are formed and mounted to normally gravitate to locking position.

The latch element 45, forming part of the supporting means G, is similar to the latch 44 except that it is not provided with an operating handle, the same being connected with the latch 44 by means of a bar H, said bar having one end pivotally connected to the member 44, between the jaws 58—58 formed integrally therewith, and the connection of the bar H with the latch 45 is effected by extending the end of the bar between the walls 60—60, similar to the walls 58—58, of the member 45 and loosely securing the same by means of a pivot pin 59. The latch 45 is adapted to have swinging movement independently of its companion member 44, due to the provision of a slot 61 formed in the end of the member H, through which the pivot 59 extends. The bracket 47 is in many respects similar to bracket 46 except that it is extended rearwardly of the hook, and a locking cam 62 is pivotally mounted between its inner and outer walls. The cam 62 is adapted to lock the latch 45 when it is in locking position beneath the door beam, and when said hook 45 is locked, it also operates to lock the other of said hooks, due to the fact that both hooks in the series are disposed to swing in the same direction and are inter-connected by means of the member H. Similarly in releasing the doors, the release of member 44 will release both of said hooks simultaneously. Thus it will be noted that the simple connection provided for the pair of hooks,

eliminates one releasing device and one locking device for each door, and at the same time assures safety to the operator, as the handle 56 is conveniently located to one side of the door, and the operator may stand out of the path of the discharging load when releasing the doors.

While I have herein shown and described what I now consider the preferred manner of carrying out my invention, the same is merely illustrative and I contemplate all changes and modifications that come within the scope of the claims appended hereto.

What I claim is:

1. In a dump car, the combination with a dumping door; of a plurality of shouldered locking hooks adapted to supportingly engage the door, said hooks being adapted to move in the same direction in and out of supporting engagement with the door; a bar connecting the hooks; a slotted connection between the bar and one of said hooks whereby said hook may have a limited degree of independent movement relatively to the bar; and means whereby the locking of said independently movable hook will also lock the remainder of the hooks.

2. In a dump car, the combination with a dumping door; of supporting means therefor, said supporting means including brackets mounted on the car above the door, and a hook pivotally connected to each of said brackets and having shouldered engagement with the door; a bar connecting the respective hooks, said bar having a pivotal connection with the respective hooks at a point intermediate the brackets and the shouldered connections with the door; locking means associated with one of said hooks; and releasing means associated with the other of said hooks.

3. In a dump car, the combination with the side wall of the car; of a dumping door; of a series of floor beams carried by the door and projecting outwardly beyond the car side; a series of locking elements carried by the car side, each of said elements being adapted to co-operate with a corresponding floor beam to maintain the door in closed position; a locking member associated with one of said locking elements to maintain the door in closed position; and means associated with another of said locking elements for releasing all of the elements in the series simultaneously.

4. In a dump car, the combination with a dumping door; of a plurality of hooks adapted to supportingly engage the door, said hooks being spaced an appreciable distance from each other and movable in the same direction into and out of engagement with the door; a bar connecting the said hooks, a slotted connection between one of said hooks and the bar; locking means associated with one of said hooks; and a handle

associated with the other of said hooks for moving both of the hooks out of engagement with the door.

5. In a dump car, the combination with a dump door; of a plurality of hooks adapted to support the door, said hooks being pivotally mounted on the car structure for movement in the same direction; a member adapted to connect said hooks, said member being in the form of a flat bar; and a plurality of spaced jaws on each of said hooks, for the reception of said bar, said bar when in operative position with respect to said hooks being within said jaws.

10. 6. In a dump car, the combination with a dump door; of a hook adapted to supportingly engage the door, said hook having spaced walls; an operating connection disposed between the said walls; and means 15 passing through the said walls for pivotally retaining the connection in operative engagement with the hook.

7. In a dump car, the combination with pivoted door closure means having a pair 20 of supporting shoulders thereon; of a pair of pivoted hooks adapted to cooperate with said shoulders to hold the door closure means in closed position; and an operative connection between said hooks arranged, upon 25 movement of one of the hooks to inoperative position, to effect simultaneous movement of the other hook to inoperative position and in the same direction about its pivot, said operative connection also permitting movement of 30 one of said hooks to operative position independent of the other; and locking means co-operable with one of said hooks whereby, upon locking of the latter, both hooks are held in locked position through the intermediary of said operative connection.

8. In a dump car, the combination with

a pivoted door having a pair of supporting shoulders thereon; of a pair of pivoted hooks arranged to swing in a common plane parallel to the pivotal axis of the door and adapted to cooperate with said shoulders to hold the door in closed position; and an operative connection between said hooks arranged, upon movement of one of the hooks to inoperative position, to effect simultaneous movement of the other hook to inoperative position and in the same direction of pivotal movement, said operative connection also permitting movement of one of said hooks to operative position independently of the other.

9. In a dump car, the combination with pivoted door closure means having a pair 40 of supporting shoulders thereon; of a pair of pivoted hooks adapted to cooperate with said shoulders to hold the door closure means in closed position; an operative connection between said hooks arranged, upon movement of one of the hooks to inoperative position, to effect simultaneous movement of the other hook to inoperative position and in the same direction about its pivot, said operative connection also permitting movement of 45 one of said hooks to operative position independent of the other; and locking means 50 co-operable with one of said hooks whereby, upon locking of the latter, both hooks are held in locked position through the intermediary of said operative connection.

In witness that I claim the foregoing I have hereunto subscribed my name this 9th day of May, 1925.

ARGYLE CAMPBELL.
